CLAIM

The ornamental design for a vehicle wheel rim, as shown and described.

DESCRIPTION

FIG. 1 is a front view of the vehicle wheel rim showing my new design; and,

FIG. 2 is a front, side perspective view thereof.

The broken lines showing of the rear portion of the vehicle wheel rim is included for the purpose of illustrating environment and forms no part of the claimed design.

1 Claim, 2 Drawing Sheets

FIG. 1

FIG. 2
